INVENTOR.

UNITED STATES PATENT OFFICE.

GEORGE B. SMITH, OF FREMONT, OHIO.

DENTAL MEDICINE-RECEPTACLE.

SPECIFICATION forming part of Letters Patent No. 732,662, dated June 30, 1903.

Application filed December 19, 1901. Serial No. 86,594. (No model.)

To all whom it may concern:

Be it known that I, GEORGE B. SMITH, a citizen of the United States, and a resident of Fremont, in the county of Sandusky and State 5 of Ohio, have invented certain new and useful Improvements in Dental Medicine-Receptacles, of which the following is a specification.

The purpose of this invention is to provide 10 a rockable and self-righting bottle for dentists' use which reduces the loss of medicine from evaporation and accident to a minimum while the bottle is still open and ready for use by the operator.

15 In general terms said invention embraces a divided rockable and self-righting bottle 1, a cap or cover 2, and a ground or other tight-fitting stopper 3.

Referring now to the drawings of my invention, Figure 1 represents the same in perspective view, a portion of the cap or cover being cut away to show other parts. Fig. 2 represents a cross-section of the bottle on the line A A of Fig. 1. Fig. 3 represents a cross- 25 section of the bottle on the line B B of Fig. 1. Fig. 4 represents a longitudinal section of the stopper on its median line. Fig. 5 represents the cap or cover.

It is well known that dentists in the practice 30 of their profession use many kinds of medicines which are more or less volatile and have to be applied by means of cotton or some other light absorbent and still other kinds, such as acids, which have to be applied by means of a suitable wire or broach, all of which under the present practice is furnished in ordinary bottles, which to prevent evaporation or accidental spilling are required to be closed after each time they are 35 used. In opening and closing these bottles and to obtain the required amount of medicine both hands are frequently required, and that, too, at a time when from the nature of the operation it is least convenient to use 40 them for that purpose, and hence much inconvenience results. I obviate these inconveniences by means of my invention.

The bottle is made rockable in form, as 45 represented in Fig. 2, and is divided into two receptacles 1^b by means of a raised bridge 1^c, over which the medicine is made to flow as

the bottle is rocked in the process of using. It is provided with a neck 1^a, as in the case of ordinary bottles, and to which the cap or cover is ground to fit.

55

The stopper 3 is formed with a conical or funnel-shaped passage extending in line with its axis, as seen in Fig. 4, the open mouth being at its external end. The province of this mouth is to receive a ball or wad of cotton 60 held by pliers or tweezers in the hand of the operator, and its capacity is accordingly. Said stopper should be adapted so that when in place its inner end will nearly touch the bridge 1^c, as shown in dotted outline in Fig. 65 3. The inner end of said passage 3^a is so contracted as to prevent most of the cotton from being forced through said passage and into the bottle, while at the same time it permits some of the fibers to come in contact 70 with and absorb some of the medicine as the bottle is rocked and the same is made to pass over the bridge and from one receptacle to the other. Said passage is also intended to accommodate the use of a suitable wire or 75 broach wound with cotton, as dentists frequently use the same in applying medicine to the nerve-canals, said wire or broach with cotton wound thereon being passed through said passage and into the bottle, and its capacity or dimensions are accordingly. Ordinarily the medicine will not rise within this 80 passage; but it may be made to rise therein by any undue rocking of the bottle; but in such cases the cotton serves to arrest the flow. 85 As observed in Fig. 3, I make the bridge lowest at its middle, and thus facilitate the use of the bottle as long as there is any medicine remaining in either receptacle. It will therefore be observed that by means of said contracted passage through the stopper not only 90 is all loss of medicine due to evaporation or accidental spilling reduced to a minimum, but at the same time the bottle is left open and ready for use, as required.

95

The neck 1^a is not made longer than necessary to receive the cap or cover, and thus by preventing the bottle from becoming top-heavy I aid in making the same self-righting.

The bottle is made self-righting within reasonable limits of use by means of its form, as represented in Fig. 2, the bottle when

rocked having a surplus of weight between its bottom and a vertical line drawn from the point of contact.

It is manifest that the bottle might be filled 5 through the passage in the stopper; but the necessities of practical construction require a large mouth through which to reach and form the two receptacles and give suitable shape to the bridge.

10 The flange 3^b forms no feature of my invention, but is convenient as a means of holding while grinding.

While these bottles may be made from other material, yet for manifest reasons I prefer 15 to make them of glass.

Having described my invention, I now claim as new—

A rockable bottle formed with two recep-

tacles or chambers divided by a bridge over which its contents is made to flow in passing 20 from one receptacle to the other, in combination with a stopper having a conical or funnel-shaped passage in line with its axis, the smaller or reduced radius of said passage being at its inner end, so adapted that when in 25 place the inner end of said stopper is in close proximity with the medicine as the same is made to pass over said bridge.

In testimony whereof I have signed my name to the foregoing specification in the 30 presence of two witnesses.

GEORGE B. SMITH.
